United States Patent Office.

FREDERIC PASSY, OF PARIS, FRANCE.

Letters Patent No. 79,253, dated June 23, 1868.

IMPROVEMENT IN ANDIRONS AND FIREPLACES.

The Schedule referred to in these Letters Patent and making part of the same.

TO ALL WHOM IT MAY CONCERN:

Be it known that I, FREDERIC PASSY, of Paris, France, have invented an Improvement in Andirons; and I do hereby declare the following to be a full, clear, and exact description of the same.

My invention consists of andirons, having channels for the passage of air, which, after being heated by contact with the heated portions of the andirons, is discharged into the apartment.

In order to enable others skilled in the art to make and use my invention, I will now proceed to describe its construction and operation, reference being had to the accompanying drawing, which forms a part of this specification, and in which—

Figure 1 is a front view of a fireplace, with my improved andirons arranged therein.

Figure 2, a plan view, partly in section.

Figure 3, a sectional elevation on the line 1-2, fig. 1.

Figures 4 and 5, detached views, drawn to a reduced scale; and

Figure 6, a front view of a fireplace, having modified forms of andirons.

E, figs. 1, 2, and 3, is an andiron, consisting, in the present instance, of a siphon-like metal tube, which is arranged within a fireplace, so that the branches, e^1 e^2 , shall be parallel to the hearth, the curved portion of the tube being nearest the back of the fireplace, and the upper branch, e^1 , communicating with the inclined portion, e^2 , of the tube, which projects into the apartment, as shown in the drawing.

The lower branch, e , rests upon the hearth, and supports the fuel, and the lower stratum of air in the apartment, entering the tube E through the end of the branch e , traverses the latter, the bent portion e^2 , and the branch e^1 , from which it flows to the inclined portion e^2 , and passes thence, in a highly-heated state, into the apartment.

Instead of a bent tube, E, the andiron may consist of a cast-metal piece, E', and an upright pipe, d, the piece E' having channels, a a' , communicating at the back of the fireplace, through a bent tube, C, the channel a' communicating also with the pipe d', and the channel a having its mouth near the level of the hearth, as shown in the drawing.

Registers may be placed both at the points where the air enters the andirons and where it leaves them, and an urn, E², or other receptacle for water, may be placed at the upper end of the andiron, as shown in fig. 6, so that the air, before leaving the andiron, shall pass in contact with the receptacle, and heat its contents.

I claim as my invention, and desire to secure by Letters Patent—

1. An andiron, having channels or passages, arranged substantially as described, so that a current of air from the lower portion of the apartment in which the andiron is placed shall pass into and through the andiron, and be discharged into the apartment in a heated state, as specified.

2. The combination of the above and a water-receptacle, arranged upon the upper end of the andiron, as and for the purpose described.

In testimony whereof, I have signed my name to this specification in the presence of two subscribing witnesses.

FREDERIC PASSY.
